UNITED STATES PATENT OFFICE.

LEMON M. REED, OF CLEVELAND, OHIO, ASSIGNOR TO THE CLEVELAND COOPERAGE AND MACHINE COMPANY, OF SAME PLACE.

HEATER FOR COOPERAGE PURPOSES.

SPECIFICATION forming part of Letters Patent No. 426,325, dated April 22, 1890.

Application filed January 23, 1890. Serial No. 337,803. (No model.)

To all whom it may concern:

Be it known that I, LEMON M. REED, of Cleveland, in the county of Cuyahoga and State of Ohio, have invented certain new and useful Improvements in Heaters for Cooperage Purposes; and I do hereby declare the following to be a full, clear, and exact description of the invention, such as will enable others skilled in the art to which it pertains to make and use the same.

My invention relates to improvements in heaters for cooperage purposes; and it consists in certain features of construction and in combination of parts hereinafter described, and pointed out in the claims.

In the manufacture of barrels and kegs, the staves having been assembled and held in place by truss-hoops, and preferably with one head in place, the barrel or keg should then be heated to shrink the wood and to set the staves in their bent position, preparatory to the final hooping, and my improved heater is adapted more especially for such purpose.

In the accompanying drawings, Figure 1 is a front elevation with a jacket or casing in section. Fig. 2 is a side elevation, partly in section. Fig. 3 is a plan in section on line xx , Fig. 2. Fig. 4 is a side elevation of one of the vertical partitions of the stove. Fig. 5 is an end view of the grate.

A represents a stove, usually of cast-iron, and preferably of the cylindrical variety shown, the same having a fuel-supply door A' and ash-pit door A^2 , the latter being provided in the usual manner with dampers for admitting air under the grate for the purposes of combustion; also, is provided a door A^3 near the bottom of the stove for the purpose of cleaning the internal lower portions of the stove and the adjacent sections of the smoke-pipe B^2 . The stove-cylinder A has internal vertical ribs a for holding in place partitions C C. These partitions extend from near the top of cylinder A—say within an inch and a half or two inches, (more or less,) downward past the ash-pit, at which point cylinder A is provided, forward and rearward, with internal horizontal ribs a' for partitions C C to rest on. Partition-plates C, along the bottom thereof, have ribs c , presenting inward or toward each other, and partitions C are notched at the lower corners thereof at $c' c'$, where these par-

tition-plates engage ribs $a' a'$, so that the top surfaces of ribs a' and ribs c are on the same horizontal plane and support plate D on the four sides thereof, the latter constituting the bottom wall of the ash-pit.

F is the grate, the same having a square hole in the front and rear sections for receiving the square portion of spindle or shaker f , on which the grate is mounted. The grate fits loosely between the plates C C, so that the grate may be sufficiently shaken or oscillated by means of the spindle or shaker.

E is a cover resting on top of the stove, and E' E' are metal plates connected with the cover by means of bolts e , and these plates are separated the one from the other, and the lower plate is separated from the cover, respectively, by means of washers or thimbles e' mounted on the bolts. Partitions C C partition off a portion of the space in the stove into diving-flues B B, and these flues discharge into chamber B' below the ash-pit, the latter connecting, as aforesaid, with smoke-pipe B^2 . It will be seen, therefore, that the fire-box is located between partitions C C and the products of combustion pass up over these partitions and down through the diving-flues into chamber B' and from thence has its exit through the smoke-pipe.

G is a jacket or casing constructed usually of sheet metal and inclosing the upper portion of the stove from about the line of the grate upward, and between this jacket and the adjacent section of stove A is inclosed a heating-chamber K, in which the barrel or keg, the one or the other, according to the size of the heater, is placed. For supporting this jacket is provided a broad flat ring H, having depending ears H', these ears being bolted to the stove. The ring has a peripheral flange h for attaching the jacket, and has a broad upturned annular flange h' , that stands off a trifle from the stove, as shown, and by being thus separated from the stove this flange does not become overheated, and serves as a shield or guard to prevent the barrel or keg from coming in contact with the stove, by reason of which the barrel or keg is not burned. Ring H is located about opposite the grate, as shown. The jacket is provided with a cover G', this cover being hinged on the rear side at g somewhat below the top of the jacket

and somewhat rearward of the latter, as shown, so that in opening the cover the latter will swing back out of the way. A metal strap g' is attached on top of the cover and extends laterally, the ends of this strap being bent down outside the cover, as shown, and to the depending ends of strap g' are attached rods I , the latter connecting at i with a lever J . This lever is pivoted at j to brackets projecting from the base of the stove, this lever serving as a treadle, and by depressing the forward member thereof cover G' is tilted upward and backward to the position shown in dotted lines, thereby exposing the heating-chamber K . Connecting at $j'j'$ with the lever or treadle are rods L , the same extending up through holes in ring H into the heating-chamber, these rods having laterally-projecting heads l for the barrel or keg to rest on. These heads l are therefore elevated simultaneously with cover G' . Jacket G is provided with a door G^2 , located opposite door A' , and by opening the former access is had to the latter whenever it is necessary to replenish the fire.

In operating the heater the operator places his foot on the forward end of the lever or treadle J and depresses it to open cover G' and to elevate heads l , and holds the parts in such position while he removes the barrel or keg from the heater and places another in position in the heater. The elevation of heads l raises the keg or barrel about a third of its length above the heater, in which position it can be easily grasped and handled, and in placing a barrel or keg in the heater with heads l elevated the keg or barrel is easily lowered into the heater for about two-thirds of its length until it rests on these heads, after which, by gradually withdrawing the foot upward from the lever, the barrel or keg is gradually lowered into the heater simultaneously with the closing of the cover. The barrel or keg M , when in position in the closed heater, the upper head m is supposed to be just above the upper plate E' , and there being several of these plates the initial heat from cover E is deflected laterally so as not to burn heads m , which latter would otherwise receive too much heat from cover E .

The device is simple and comparatively in-

expensive, and occupies but a little more floor space than the barrel or keg it is intended to accommodate, and from the fact that the barrel or keg is entirely inclosed in 55 the heating-chamber the work is effective and quickly done.

In Fig. 4 the partition-plate C is shown in three pieces. This construction is preferable because the central portion of the plate, being opposite to the fire, is likely to burn out soonest, and therefore a considerable saving is effected by having the plate in pieces, so that the central section thereof can be renewed more frequently than the end sections. 65

What I claim is—

1. A heater for cooperage, comprising a stove having diving-flues connecting with a smoke-pipe at or near the bottom of the stove, a jacket surrounding the upper section of the stove 70 and inclosing a heating-chamber adapted to receive a barrel or keg, according to the size of the heater, a tilting cover connected with the heater, and a treadle operatively connected with such cover for opening and closing the 75 same, substantially as set forth.

2. The combination, with stove, jacket, and inclosed heating-chamber, substantially as indicated, a tilting cover for opening and closing such heating-chamber, and a treadle operatively connected with such cover for opening and closing the same, of rods connected with such treadle, such rods extending into the heating-chamber and having heads adapted to support a barrel or keg in position in the 85 heating-chamber, such heads being simultaneously elevated and depressed with the tilting cover, substantially as set forth.

3. The combination, with stove, jacket, and inclosed heating-chamber, substantially as indicated, of a cover for the stove-top, such cover being provided above with a series of lateral plates, the cover and the different plates being separated the one from the other, substantially as set forth. 90

In testimony whereof I sign this specification in the presence of two witnesses this 4th day of January, 1890.

LEMON M. REED.
